UNITED STATES PATENT OFFICE

ROBERT HARBEN WHITELEGG, OF DISLEY, ENGLAND

FUEL BUNKER FOR THE STEAM GENERATORS OF LOCOMOTIVES, MARINE AND STATIONARY ENGINES, AND PLANT

Application filed April 4, 1929, Serial No. 352,541, and in Great Britain June 15, 1928.

This invention relates principally to steam locomotives but may be applied to stationary, marine or other plant, and has for its object the provision of means whereby the trimming of coal or other fuel carried in bunkers may be performed mechanically and in a more convenient and efficient manner than heretofore.

In locomotive practice it is usual to carry the coal or similar fuel in a bunker or container, attached to the framework of the locomotive or its tender and in order to trim the fuel to a convenient place for the fireman, the sides and bottom of the bunker are sloped to a greater or lesser degree with the object of helping the fuel to slide towards the shovelling plate or opening. These "self-trimming" methods are not satisfactory inasmuch that it is not often practicable to provide sloping sides and bottoms of sufficient incline to cause the coal to slide, and it is therefore necessary to shovel the coal from the back of the bunker to the front by hand, thus entailing considerable extra work for the fireman or other attendant.

To overcome this difficulty devices have been suggested for pushing forward the fuel by means of a steam cylinder and ram, but these appliances are not satisfactory in service owing to small coal or other dirt quickly preventing movement of the ram due to clogging.

The present invention consists of a fuel bunker for the steam generators of locomotive, marine and stationary engines and plant consisting of a closed vessel or container provided with filling and delivery openings and doors the vessel being rotatively mounted with its lowermost side inclined.

A revolvable bunker or container made in accordance with the present invention may be of any suitable shape or section but is preferably of circular cross section and tapering in diameter from front to back, the larger diameter being at the forward end near to the driver's footplate. The axis of this taper cylinder may be horizontal but will preferably be higher at the rear than at the front, the top side of the cylinder being practically horizontal, thus giving the bottom side of the cylinder a steep slope. The cylinder or

container may be supported by suitable bearings from the framework or attachments of the locomotive or tender, and suitable mechanism for causing the cylinder to revolve may be attached to the cylinder and the framework. At suitable places in the circumference of the cylinder will be provided doors, to open for filling in the fuel and to close for prevention of losing the fuel during rotation of the cylinder. To facilitate the filling of the container or bunker, the filling doors may be made so as to form a hopper when open, and suitable abutments may be fixed to the framework or the water tank to support the doors against the weight of the fuel as it falls from the tipping wagons or grab. I may provide the container with sliding doors, and hopper plates may be fixed to the framework or to the water tank or other suitable part of the locomotive or tender or other foundation. The inside of the cylinder may be smooth or provided with guides or vanes arranged spirally or in any other suitable way to help forward the coal. The bearings of the cylinder may be provided with rollers or other anti-frictional devices and suitable clips for maintaining contact between the cylinder and the bearings may be provided as desired.

The mechanism for rotating the cylinder may be operated by hand or by steam or other suitable motor. One method of revolving the cylinder or container may be by a toothed ring fixed to the outside of the cylinder and gearing with a pinion or worm operated by a shaft and handle from the driver's footplate. The toothed ring may conveniently be made to form the runway for the supporting roller bearings. Another method may be by gearing attached to the axis of the cylinder or any other suitable method may be used.

At the front or footplate end of the cylinder or container may be provided one or more doors and shovelling plates so arranged that an aperture or apertures in the cylinder front end may be opened or closed as desired, to obtain fuel from the container or to seal up the container during the process of revolving. The shovelling plate may be made to form the door also, and flexible side shields

may be provided if desired. Doors may also be provided in the end plate for access to the container.

Revolving the container will precipitate the fuel towards the large end and thus bring the fuel from the middle and rear of the container to the front where it is convenient for the fireman to handle. Any number of doors may be provided at the front end, thus limiting the amount of revolution required. A further advantage of this closed form of bunker, is that the coal dust cannot be blown on to the footplate of the engine when travelling. The apparatus may be applied to any form of locomotive or tender or to stationary, marine or any other form of bunker or container.

It will be advantageous under certain conditions to make the shovelling door and platform stationary so as to always present a fixed platform, without the necessity for revolving the container a definite amount, and the present invention also comprises a revolvable fuel container or bunker in which the end for the discharge of the fuel is closed by a separate structure or casting; this structure or casting being fixed to the framework of the locomotive or tender or to the framework of the vessel or on the ground or other convenient place, and preferably containing bearings for carrying the revolvable container. Outlets for the fuel and suitable shovelling platforms and doors may be provided as part of the structure or casting, also doors for access to the fuel container.

Another feature of the invention comprises a conveyor for transporting the fuel from the delivery platform or door at the fixed end piece of the rotary container to the firebox or other part of the plant; so as to avoid the necessity for manhandling the fuel. The conveyor may be of the scroll, screw or any other suitable method and operated by steam or other motor, and the fuel may be crushed, broken or pulverized by any suitable method on its way from the container to the combustion chamber. Steam for the operating motor may be taken from the boiler using the fuel or from any other source of supply, or the motor may be driven by any other means.

The pulverizer may be of any suitable form and may be part of the conveyor system or separate as desired and suitable distributors and burners for either pulverized or other fuel may be provided. I may provide a pulverizer and suitable blowing apparatus for conveying the pulverized fuel, or any combination of mechanical conveyor and blowing apparatus.

A manner of carrying out the invention is illustrated by the accompanying drawing wherein Figure 1 is a side elevation and Figure 2 an end elevation of the tender portion of a locomotive, while Figures 3 and 4 are

similar views of a locomotive of the "Garratt" type.

In Figures 1 and 2, A is the tender with water tank and framework carried on wheels B. The tender is attached to the locomotive C at D. The fuel bunker is a closed rotary vessel or container E which is at its front end supported upon and carried by bearings in the form of rollers F, F and is rotated by means of toothed gearing G operated by a handle H. The rear end of the container E is supported by a central bearing F¹. The rotary vessel E is provided with hinged filling doors J and sliding filling doors J¹.

In some cases either the sliding doors or the hinged doors are dispensed with, and when hinged doors are used they may be designed when opened out as in Figure 2 to form a fuel hopper.

The container E has a front fixture K and may be provided with rollers F¹, arranged to form anti-friction bearings for the container. Either the rollers F¹ or F may be dispensed with. A shovelling plate or platform L is provided at a fuel delivery outlet L¹, also doors M are provided in the front fixture K, and side shields S, S, are arranged at the sides of the shovelling platform L.

The fuel is delivered on to a footplate N for hand firing and into a conveyor system P for mechanical firing. In the system shown a horizontal conveyor P delivers fuel to the lower end of a vertical conveyor P¹ which delivers the fuel into the furnace Q of the locomotive boiler. Alternatively the conveyor P¹ delivers fuel through a pipe p into a power driven pulverizer T having a blower U which conveys pulverized fuel through the pipe u into the furnace Q.

In the application of the invention as applied to a "Garratt" articulated locomotive, as shown in Figures 3 and 4, the corresponding parts are given the same reference numerals, and as the hind power unit carries the bearings F and F¹ of the receiver E, it is given the same reference numeral as the tender A of Figures 1 and 2.

The gear G for rotating the receiver, instead of being driven by hand may be driven by a steam or other motor.

What I claim and desire to secure by Letters Patent is:—

1. A fuel bunker for the steam generators of locomotive, marine and stationary engines and plant consisting of a closed vessel or container provided with filling and delivery openings and doors the vessel being rotatively mounted on bearings with its lowermost side inclined and provided with mechanism for rotating.

2. A fuel bunker for steam generators of locomotives, marine and stationary engines and plant, consisting of a closed rotary vessel or container of which the lowermost side is inclined downwards towards the fuel dis-

charge end which is closed by a separate fixed structure or casting having a fuel delivery outlet.

3. A fuel bunker in accordance with claim 1, wherein the vessel is tapering in cross section and mounted with its uppermost side horizontal or approaching thereto.

4. A fuel bunker in accordance with claim 1, wherein the vessel is mounted on rollers or other anti-friction bearings.

5. A fuel bunker in accordance with claim 1, wherein the filling doors are adapted to open out to form a hopper.

6. A fuel bunker in accordance with claim 1, wherein sliding filling doors are provided and separate hopper plates.

7. A fuel bunker in accordance with claim 1, wherein the shovelling plate or plates is or are adapted to form a door or doors to close openings during rotation of the bunker.

8. A fuel bunker in accordance with claim 1, wherein side shields are used to form the sides of the shovelling platform.

9. A fuel bunker in accordance with claim 2 wherein the separate fixed structure or casting contains bearings for carrying the rotary vessel or container.

10. A fuel bunker in accordance with claim 2 wherein on the separate fixed structure or casting is provided a shovelling platform.

11. A fuel bunker in accordance with claim 2, wherein the separate fixed structure or casting is also provided with one or more doors for access to the fuel container.

12. A fuel bunker in accordance with claim 2 wherein is provided a conveyor for conveying fuel from the outlet of the separate fixed structure to the fire box or other receiver.

13. A fuel bunker in accordance with claim 2, wherein a fuel reducer is provided in the conveyor system.

14. A fuel bunker in accordance with claim 2 wherein a power driven fuel reducer and furnace feed blower is provided in the conveyor system.

15. A fuel bunker in accordance with claim 1, wherein a power driven fuel pulverizer is provided with blowing apparatus for conveying the pulverized fuel into the furnace.

16. A fuel bunker in accordance with claim 1, wherein one or more doors are provided in the front end for access to the fuel container.

55 In witness whereof I affix my signature.
ROBERT HARBEN WHITELEGG.
